UNITED STATES PATENT OFFICE

2,000,775

REFRIGERATION APPARATUS

John W. McNulty, Ridley Park, Pa., assignor to
Westinghouse Electric & Manufacturing Com-
pany, East Pittsburgh, Pa., a corporation of
Pennsylvania

Application November 4, 1932, Serial No. 641,296

12 Claims. (Cl. 62—152)

My invention relates to refrigerating apparatus and more particularly to that type wherein liquid refrigerant is cooled by partial vaporization in a spray tank, and the cooled liquid refrigerant is conducted away to apparatus wherein it absorbs heat from the media to be cooled.

An example of apparatus of this type here-
10 tofore known to me, comprises a tank having a spraying device therein, conduit means for circu-
lating cooled water from the lower portion of the tank, through a heat exchanger where it ab-
sorbs heat from the media to be cooled, and back
15 to the spray device. A steam-motivated ejector is provided for reducing the pressure of the in-
terior of the tank and conducting away that portion of the water which is vaporized. As is well known the partial vaporization of the water in the tank, which is due to the spraying com-
bined with the low pressure condition, results in
20 the cooling of the remaining water by the ab-
sorption therefrom of the latent heat of vapor-
ization required to evaporate the vaporized wa-
ter. This type of apparatus operates with the
25 highest degree of efficiency when a minimum of liquid refrigerant is carried away by the vacuum pro-
ducing means, and when there is a minimum
difference between the temperature of the cooled refrigerant in the bottom of the tank and the
30 temperature corresponding to the vacuum in the tank.

Difficulty has been experienced in the opera-
tion of prior apparatus of this character due to
the fact that the vacuum producing means, which in the above example is the steam-moti-
35 vated ejector, carries off with the vapor stream a substantial amount of liquid refrigerant which results both in the loss of refrigerant and the inability of the ejector to effect as low a vacuum in the tank as it otherwise would. A further difficulty experienced with this apparatus is the ineffectual evaporation of the liquid refrigerant sprayed in the tank. This latter is due in part to the inability of the ejector to provide a suffi-
40 cient vacuum for the reason just explained, and also due to the failure of prior structures to maintain the small particles of refrigerant in a low pressure zone for a sufficient length of time.

It is, therefore, an object of this invention to obviate the above difficulties by providing an improved form of spray tank, spray device, and baffle structure which are so constructed and arranged as to separate effectively the liquid refrigerant from the vapor stream by the utilization of the law of inertia, to lower to the minimum the rate of flow of the vapor stream, to

produce an extremely fine spray of the liquid refrigerant in the tank and to provide relatively long paths of travel for the liquid refrigerant.

A further object is to provide refrigerating apparatus of this character which operates effec-
tively and efficiently and one that requires little attention.

A still further object is to provide apparatus of this character wherein the amount of liquid refrigerant in the system is maintained constant.

These and other objects are effected by my invention, as will be apparent from the following description and claims taken in connection with the accompanying drawing, forming a part of this application, in which:

Fig. 1 is a diagrammatic view illustrating a complete refrigerating system constructed in accordance with the present invention.

Fig. 2 is a vertical section through my im-
proved evaporator or spray tank, the section
being taken on the line II—II of Fig. 3; and,

Fig. 3 is a horizontal sectional view of the spray tank taken on the line III—III of Fig. 2.

Referring now in detail to the construction illustrated, it will be observed that I have shown in Fig. 1 a complete refrigerating system comprising a cooling evaporator or spray tank 10 which is maintained in a vacuous condition by an ejector 11 motivated by steam from a supply pipe 11a and discharging into a suitable con-
denser, for example, the surface condenser 12. Cooling water is supplied to the condenser from a suitable source of supply by a pipe 13 and pump 14 and is conducted away by a pipe 15. Condensate may be removed from the con-
denser by any suitable means such, for example, as a pump 16. The non-condensable gases are removed from the condenser and vacuum main-
tained therein by an ejector 17 also motivated by steam from the pipe 11a, or from a separate source if desired.

Refrigerant, which in the present case is water, is supplied to the tank by means of an annular manifold 18 having spray nozzles 19 which produce a finely divided spray (see Figs. 45 2 and 3). As is well known, the low pressure condition in the tank produced by the ejector 11 causes a certain portion of the water to change into a vapor and the latter is conducted away by the ejector 11. The latent heat of vaporization required to evaporate the water is absorbed from the unvaporized water, thereby cooling the latter. The water gravitates to the lower portion of the tank, the upper level of which is indicated at 20.

The cooled water in the tank may be utilized for any desired purpose. In the drawing, I have shown it as being utilized in an air conditioning apparatus 21 for buildings or the like. The apparatus 21 is shown as comprising a tubular heat exchanger 22 through which cooled water from the tank 10 is circulated. The tank 10 is connected to the heat exchanger by a pipe 23 and the warm water is conducted back to the tank from the heat exchanger by a pipe 24 connected to the spray manifold 18. A pump 25 provides for the circulation of the water from the tank 10 through the heat exchanger and back to the manifold. Air to be cooled is forced around the tubes of the exchanger 22 by a fan 26 and conducted to the rooms to be cooled by a conduit 27.

In order that a constant supply of refrigerant be maintained in the system, I provide for the addition of make-up water as the level of water in the tank is lowered by the loss of vapor. As shown, the reference numeral 28 indicates a pipe which may be connected to any suitable source of water supply. The supply pipe 28 is connected to the pipe 24 leading to the supply manifold 18. A valve 29 controls the flow of water to the pipe 24. The valve 29 is operated by a float mechanism 30 comprising a float chamber 31 connected to the water in the tank, a float 32, lever 33 and link 34 connected to the valve. As the level of water falls in the tank, the float mechanism operates to open the valve and add water to the system.

In the preferred embodiment shown, the spray tank 10 is disposed vertically and comprises a funnel-shaped bottom wall 35, a top wall 36, and a cylindrical side wall 37 joining the walls 35 and 36 and having an opening 38 in the mid-portion thereof providing communication between the inlet of the ejector and the interior of the tank. The water supply pipe 24 enters the wall 37 through an opening 39 and is connected to the manifold 18, as shown.

A sleeve-like baffle 40 is suspended within the tank by suitable brackets 41, the manifold 18 fitting within the interior of the baffle 40 at the mid-point and disposed in a plane normal to the axis of the baffle. The baffle 40 is arranged with its axis parallel to and spaced from the vertical axis of the tank 10 so as to provide between the baffle 40 and wall 37 a passage 42 which progressively increases in size as the outlet opening 38 is approached. The top of the baffle is spaced from the top 35 of the tank and the bottom of the baffle is disposed above the water level 20 so as to provide free and open communication between the interior of the baffle and the passage 42. A second baffle 43 is disposed between the baffle 40 and the wall 37 and over the outlet opening 38 for a purpose which will presently appear.

The above described tank, baffle and manifold structure provides for extremely efficient operation of the refrigerating system. The manifold 18 being disposed in the manner shown with the nozzles 19 directed toward the center thereof, results in the production of an extremely fine mist or spray which travels both upwardly and downwardly and around the sides 70 of the baffle 40 and into the passage 42. The baffles 40 and 43 are so arranged as to direct all particles of water away from the outlet opening 38 and downwardly toward the bottom of the tank. In order for any particles of water 75 to enter the outlet 38, it is necessary for their

direction of flow to be reversed after such particles have started gravitating toward the bottom. The law of inertia opposes any such reversal and it is therefore apparent that an effective separation of the water particles from the vapor is effected. In addition, as the baffle 40 is disposed eccentrically with respect to the tank, and thereby provides a passage of varying area with the greatest distance between the baffle and tank being at the outlet opening 38, a minimum of restriction is offered to the flow of vapor to the outlet with a consequent minimum rate of flow of vapor in the tank. This latter serves to preclude the entrainment in the outgoing vapor stream of any particles of water.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:—

1. In refrigerating apparatus, the combination of a spray tank comprising end walls and a tubular wall joining the end walls; a sleeve-like baffle element arranged within the tank with the axis thereof disposed substantially parallel to the axis of the tubular wall; the baffle element being spaced from the tubular wall of the tank to provide a continuous passage therebetween, and the ends of the baffle being spaced from the end walls of the tank to provide communication between the interior of the baffle and the passage; means disposed within the baffle for spraying liquid refrigerant into the tank; means communicating directly with the passage at a point intermediate the ends of the baffle for effecting a vacuous condition inside of the tank; and means for withdrawing cooled liquid from the tank.

2. Refrigerating apparatus according to claim 1 wherein the sleeve-like baffle element is disposed eccentrically with respect to the tubular wall of the tank and in such a manner that the distance between the baffle element and the tubular wall is greatest adjacent the point where the vacuum producing means communicates with the passage.

3. Refrigerating apparatus according to claim 1, wherein the refrigerant spray means comprises an annular row of nozzles disposed adjacent the inner surface of the baffle and arranged to direct a finely divided spray toward the center of the baffle.

4. Refrigerating apparatus according to claim 1 wherein the refrigerant spray means comprises an annular manifold disposed in a plane normal to the axis of the baffle and having nozzle openings directed toward the center thereof.

5. Refrigerating apparatus according to claim 1 wherein the refrigerant used is water and the vacuum producing means is a steam motivated ejector.

6. In refrigerating apparatus, the combination of a vertically-disposed spray tank comprising a top wall, a bottom wall, and a cylindrical side wall joining the top and bottom walls; a sleeve-like baffle element disposed within the tank with the axis thereof vertical, and being spaced from the side wall of the tank to provide a continuous passage thereabout and the ends of the baffle element being spaced from the top and bottom

- walls respectively to provide communication between the interior of the baffle and the passage; and means disposed within the baffle for spraying liquid refrigerant into the tank; the side 5 wall of the tank having an outlet opening opposite the baffle; means communicating with said opening for producing a vacuous condition in the tank; and means for withdrawing cooled liquid from the tank.
- 10 7. Refrigerating apparatus according to claim 6 wherein a second baffle is provided which is disposed within the passage and above the outlet opening.
8. Refrigerating apparatus according to claim 15 6 wherein water is used as a refrigerant and means is provided for automatically maintaining a predetermined water level in the bottom of the tank and below the lower end of the baffle.
- 20 9. In refrigerating apparatus, the combination of a spray tank comprising end walls and a tubular wall joining the end wall; a sleeve-like baffle element arranged within the tank with the axis thereof disposed substantially parallel to 25 the axis of the tubular wall; the baffle element being spaced from the tubular wall of the tank to provide a continuous passage therebetween, and the ends of the baffle being spaced from the end walls of the tank to provide communication 30 between the interior of the baffle and the passage; means disposed within the baffle for spraying liquid refrigerant into the tank; and means communicating directly with the passage at a point intermediate the ends of the baffle for effecting a vacuous condition inside of the tank, the sleeve-like baffle element being disposed eccentrically with respect to the tubular wall of the tank and in such a manner that the distance 35 between the baffle element and the tubular wall is greatest adjacent the point where the vacuum producing means communicates with the passage.
10. In refrigerating apparatus, the combination of an evaporating chamber having a vapor 40 outlet, means for discharging liquid to be cooled into said chamber, a baffle element disposed between and extending upwardly from said
- vapor outlet and the point at which said liquid is discharged, the interior space adjacent the vapor outlet and the interior space adjacent said point at which liquid is discharged being in communication with each other at a level spaced above said outlet and said discharge point, means for withdrawing vapor through said vapor outlet to effect cooling of the liquid in the chamber by partial evaporation thereof, and means for withdrawing cooled liquid from the 10 chamber.
11. In refrigerating apparatus, the combination of an evaporating chamber having a vapor outlet, means for discharging liquid to be cooled into said chamber, a baffle element disposed between and extending upwardly and downwardly from said vapor outlet and the point at which liquid is discharged, the interior space adjacent the vapor outlet and the interior space adjacent said point at which liquid is discharged 15 being in communication with each other at a level spaced above and at a level spaced below said outlet and said discharge point, means for withdrawing vapor through said vapor outlet to effect cooling of the liquid in the chamber by 20 partial evaporation thereof, and means for withdrawing cooled liquid from the chamber.
12. In refrigerating apparatus, the combination of an evaporating chamber for containing liquid to be cooled by partial evaporation, means 25 for withdrawing vapor from said chamber to effect said partial evaporation, a tubular heat exchanger disposed exteriorly of said chamber, means for circulating air to be cooled around the tubes of said heat exchanger, and means for 30 circulating liquid cooled in said chamber and collecting in the bottom thereof through said heat exchanger and discharging the same into said chamber above the liquid level therein, means for adding make-up liquid to said circulating liquid after it leaves said heat exchanger and before it is discharged into said chamber, and means operable automatically in response 35 to liquid level in said chamber for regulating the flow of said make-up liquid. 40
